[57] CLAIM

The ornamental design for a document attachable calling card, as shown and described.

DESCRIPTION

FIG. 1 is a front perspective view of a document attachable calling card showing my new design;

FIG. 2 is a front elevational view thereof;

FIG. 3 is a side elevational view thereof;

FIG. 4 is a rear elevational view thereof;

FIG. 5 is the opposite side elevational view thereof;

FIG. 6 is a top view thereof;

FIG. 7 is a bottom view thereof; and

The broken line showing of the book is for illustrative purposes only and forms no part of the claimed design.
